CLAIM

The ornamental design for a forklift, as shown and described.

DESCRIPTION

FIG. 1 is a front elevational view of a forklift embodying a design;
FIG. 2 is a rear elevational view of a forklift embodying the design;
FIG. 3 is a left side elevational view of a forklift embodying the design;
FIG. 4 is a right side elevational view of a forklift embodying the design;
FIG. 5 is a top plan view of a forklift embodying the design;
FIG. 6 is a front perspective view of a forklift embodying the design;
FIG. 7 is a rear perspective view of a forklift embodying the design; and,
FIG. 8 is a rear perspective view of a forklift embodying the design.

1 Claim, 8 Drawing Sheets(56)
